UNITED STATES PATENT OFFICE.

THOMAS I. POTTER, OF PORTLAND, OREGON.

ROTARY EXPANSION VALVE.

Application filed November 10, 1926 Serial No. 147,535.

This invention relates generally to the art of mechanical refrigeration, and particularly to expansion valves for delivering and regulating the flow of liquid refrigerant to an expansion system, and for the transfer of gases from higher to lower pressures.

The main object of this invention is to provide a mechanically operated valve whereby small quantities of liquid refrigerant can be accurately measured and delivered to an expansion system without the employment of small or delicate or expensive parts or those subject to objectionable wear or deterioration such as is common with ordinary expansion valves.

The second object is to so construct the device that it will be capable of handling various volatile and expandable substances by utilizing their natural tendency to expand as a means for propelling same through a transfer device.

The third object is to so construct the valve that any foreign matter seeking lodgment therein will be carried away, due to the operation of the valve itself.

These, and other objects, will become more apparent from the specification following as illustrated in the accompanying drawing, in which:

Figure 1 is a fragmentary sectional view through the valve and a portion of the compressor case on which it is mounted showing the driving shaft and its bearing. Figure 2 is a transverse section taken along the line 2—2 in Figure 1. Figure 3 is an enlarged section showing the intake pocket registering with the measuring pocket. Figure 4 is an enlarged section showing the discharge pocket receiving a charge from the measuring pocket. Figure 5 is a section through the valve showing all of the pockets and ports out of register. Figure 6 illustrates a condition similar to Figure 3 in which the intake pocket is discharging refrigerant into the measuring pocket. Figure 7 is similar to Figures 5 and 6 but showing the intake pocket registering with the intake port and the discharge pocket registering with the discharge port. Figure 8 is similar to Figures 5, 6 and 7 but showing only the discharge pocket registering with the measuring pocket. Figure 9 is an outside elevation of the device as a separate unit.

Similar numbers of reference refer to similar parts throughout the several views.

Referring in detail to the drawings, there is illustrated a portion of a compressor case 10 in which is rotatably mounted a valve disk 11 whose wearing or seat side is cut away at the center 12 for seating purposes. The rear side of the disk 11 is provided with a slot 13 which receives the flattened end 14 of the shaft 15 which journals in the bearing 16. A friction washer 17 is provided in the members 14 and 16. A spring 18 in the shaft 15 holds the valve disk to its seat. In the seat 19 of the valve are provided two curved recesses or pockets 20 and 21. The pocket 20 on the larger radius will be referred to as the intake pocket and the pocket 21 on the smaller radius will be referred to as the discharge pocket.

An intake pipe 22 from the receiver passes through the case 10 in the path of the pocket 20. A discharge pipe 23 which connects with an expansion system (not shown) passes through the case 10 in the path of the pocket 21.

On the side of the case 10 approximately equidistant from the pipes 22 and 23 is formed a stuffing box 24 provided with a gland 25 through which passes a threaded stem 26 whose position in the hole 27 determines the amount of refrigerant delivered at each revolution of the shaft 15. The hole 27 will be referred to as a measuring pocket.

In Figure 9 the elements are similar to those in Figure 8 except that the casing 28 encloses the valve and the stuffing box 29 surrounds the shaft 15, which is provided with a pulley 30 for driving purposes. It is preferable to provide a hole 31 in the disk 11 for the balancing of pressure and to insure proper lubrication of the disk. Lubricant 32 may be admitted through the pipe 33 in the casing 28, which pipe may also serve for providing a pressure within the casing 28 in event it is desired to seat the disk by means of fluid pressure, as well as spring pressure.

The operation of the valve is as follows: Assuming that the shaft 15 is being rotated and that the pipe 22 is connected with a receiver and the pipe 23 is connected with an expansion system and that the pipe 33 is connected with a suitable pressure maintaining apparatus, a double or two complete cycles will be described, including the original loading of the valve and the second or natural functioning of the valve, which is the working cycle. It is to be understood that the

first cycle described is only that of the first rotation of the valve, although it is possible that in some instances it would not be operating at its full efficiency until a number of revolutions had been made.

It is assumed that the pockets 20 and 21, as well as the measuring pocket 27, are empty and that the valve moves in the direction indicated in Figures 5 to 8 inclusive. The first 10 step in the cycle is illustrated in Figure 7 in which the pocket 21 registers with the discharge port 23 causing a partial vacuum to be established in the pocket 21. While the pocket 20 has been registering with the port 22 practically no fluid will enter this port, owing to the fact that no reduced pressure exists within the pocket 20.

As the disk rotates to the position shown in Figure 8 it will be observed that the pocket 21 registers with the measuring pocket 27 during which time there is a balancing of pressure in which there is a slight drop in the measuring pocket pressure and a slight rise in the discharge pocket pressure.

25 In Figure 5 is illustrated a condition of overlap in which there is no connection between any of the ports and pockets. In Figure 6 the empty pocket 20 is passing the empty pocket 27. However, at the beginning 30 of the second revolution the more or less complete vacuum in the pocket 20 will permit fluid to enter the pocket 20 by way of the port 22, due to its combined expansion and occupancy of the previously evacuated pocket 35 20. This fluid remains in the pocket 20 until it has again registered with the measuring pocket 27, whose somewhat reduced pressure permits of a still further expansion of the fluid from the pocket 20 into the measuring pocket 27 where it remains until the discharge pocket 21, which has now been subjected to a reduced pressure, crosses or registers with the measuring pocket 27.

40 The liquid now is transferred by a still further expansion into the discharge pocket from which it later escapes through the port 23.

45 While the description of the double cycle may appear somewhat involved, what actually transpires is that a partial vacuum is established on the discharge pocket 21 every 50 time it registers with its port 23 and in passing the measuring pocket the evacuated discharge pocket empties the measuring pocket 55 and later discharges its own contents into an expansion system, or as otherwise seems fit.

The function of the intake pocket is merely to transfer fluids from the intake port to the empty measuring chamber from which it is 60 picked up by the discharge pocket, as above described.

I claim:

1. An expansion valve having a pair of relatively movable contacting members, one 65 of said members having a measuring pocket

and inlet and outlet ports formed therein; and a second member having a pair of transfer pockets therein each of which registers only with its respective inlet or outlet port and both of which transfer pockets can register with said measuring pocket. 70

2. A rotary valve having a body; a disk journaling in the inside of said body; means for maintaining pressure against said disk to hold it to its seat, said body having an 75 intake port opening through same extending to the valve seat, said disk having an intake pocket adapted to register with said intake port intermittently during the rotation of said disk, said disk also having a discharge 80 pocket on a radius different than said intake pocket, said body also having a discharge port opening adapted to register intermittently with said discharge pocket during the rotation of said disk, said pocket also having a variable size measuring pocket adapted to register with both of said intake and discharge pockets alternately. 85

3. A valve for delivering measured quantities of an expansible fluid from a relatively high pressure zone to a lower pressure zone consisting of a stationary measuring pocket; and two associated movable transfer chambers adapted to register therewith successively in a manner that the higher pressure 95 fluid may be admitted to the first moving pocket and transferred thereby into said measuring pocket and then expanded from there into the second transfer pocket from which it is carried to its point of discharge. 100

4. A valve for handling expansible fluids consisting of a stationary member; a movable member seated against said stationary member, one of said members having inlet and outlet ports formed therein as well as 105 a measuring pocket provided with means for varying its cubical capacity, the second member having a pair of transfer pockets formed therein facing said first member, said transfer pockets traveling over separate paths on said seat, each of said pockets registering with an outlet and inlet port during its travel during which travel both of said transfer ports can register successively with said measuring port. 110

5. A rotary valve having rotatably mounted therein a seated disk having pockets formed in its seating face and an associated chamber adapted to receive the contents of one pocket and transfer same into the second pocket during the rotation of said disk; means for admitting liquid to one of said disk pockets; and a second means for receiving liquid from the second pocket. 120

6. A rotary valve having rotatably mounted therein a seated disk having pockets formed in its seating face and an associated adjustable chamber adapted to receive the contents of one pocket and transfer same into the second pocket during the rotation of said 125 130

disk; and means for receiving liquid from the second pocket.

7. A rotary expansion valve consisting of a rotatable disk; a body forming a journal for said disk and having an adjustable measuring pocket formed therein facing the seat of said disk, said body also having a pair of ports passing through same and opening

against the seat of said disk, said disk having a pair of curved pockets formed in its seat concentric therewith at unequal radii, each of said curved pockets registering with its respective port and both of said curved pockets registering with said measuring pocket.

THOMAS I. POTTER.
